[57] **CLAIM**

The ornamental design for a vehicle body, as shown and described.

DESCRIPTION

FIG. 1 is a front perspective view illustrating a vehicle body constructed in accordance with the teachings of the present invention.

FIG. 2 is a side view thereof, it will be understood that the side opposite to that shown is a substantial mirror image thereof; and,

FIG. 3 is a rear perspective view thereof.

It will be understood that the broken lines illustrating tires and wheels throughout the drawings are for illustrative purposes only and form no part of the subject invention. The top of the vehicle is substantially plain and unornamented.
